INVENTOR
HARRY C. MALLORY
BY John E. Hubbard
ATTORNEY

UNITED STATES PATENT OFFICE.

HARRY C. MALLORY, OF NEW YORK, N. Y.; SUE R. MALLORY ADMINISTRATRIX OF
SAID HARRY C. MALLORY, DECEASED.

CONDENSER.

Application filed March 29, 1923. Serial No. 628,613.

To all whom it may concern:

Be it known that I, HARRY C. MALLORY, citizen of the United States, and resident of New York city, in the county of New York 5 and State of New York, have invented certain new and useful Improvements in Condensers, of which the following is a specification.

My present invention consists in an improved condenser primarily devised for use in that type of engine cooling system especially adapted for use in automobile and analogous internal combustion engines, in which practically all, or at least the major 15 portion, of the heat abstracted from the engine, is normally utilized in vaporizing the cooling liquid, and is dissipated in a condenser wherein the vapor is condensed, the system comprising provisions for admitting 20 air to and withdrawing it from the cooling system, as required to maintain a vapor pressure in the system which is approximately constant and less than that in the atmosphere, so that an approximately constant and suitably low boiling temperature 25 in the engine cooling space is maintained.

The general object of my present invention is to provide an improved condenser for the use specified, and in particular to provide a condenser construction facilitating the withdrawal of air from the condenser with a minimum admixture of water therewith, even though the condenser receive appreciable quantities of water in liquid form 35 as well as water vapor from the engine cooling space or spaces.

The various features of novelty which characterize my invention are pointed out with particularity in the claims annexed to 40 and forming a part of this specification. For a better understanding of my invention, however, its advantages and specific objects attained with its use, reference should be had to the accompanying drawings and descriptive matter in which I have 45 illustrated and described preferred embodiments of my invention.

Of the drawings:

Fig. 1 is an elevation with parts broken 50 away and in section, of an engine cooling system including one form of my improved condenser;

Fig. 2 is a section on the line 2—2 of Fig. 1;

Fig. 3 is a partial section on the line 3—3 of Fig. 2; and

Fig. 4 is a view taken similarly to Fig. 2 illustrating a modified construction.

In Figs. 1, 2 and 3, I have illustrated the use of a preferred form of my improved condenser in an engine cooling system comprising a cooling liquid jacket A for the cylinders A⁵ of an ordinary internal combustion automobile engine. An inlet A' is provided at the bottom of the jacket cooling space for the cooling liquid which will ordinarily be water, or a water and alcohol mixture, and A² represents the outlet for vapor which also serves as an overflow outlet for the cooling fluid. The outlet A² is 60 connected by a conduit C, which may include the usual flexible coupling C', to the steam inlet space B' of the condenser B. From the bottom space B², or hotwell, of the condenser B, a conduit D runs to the inlet of the circulating pump E. The latter has its outlet connected by a pipe D' to the jacket inlet A'. The pump E is driven from the main engine shaft through the conventionally illustrated speed reducing gear 65 F, which also drives the ordinary condenser cooling fan G. To prevent drainage of the jacket when the pump E is not running the pipe D' is in the form of a goose neck with the top of the goose neck adjacent the top 70 of the jacket A, and is connected to the condenser by a pressure equalizing pipe connection D² to avoid siphonage.

The condenser B, in the preferred construction illustrated in Figs. 1, 2, and 3, 75 comprises a condensing core which may be formed out of horizontal tubes b having their ends expanded and soldered together to close the ends of the intertube space, as in well known types of radiators used in 80 automobile engine cooling systems of the water circulation type. The core does not entirely fill the casing of the condenser, but, on the contrary, is spaced away from the top of the latter to provide the condenser inlet space B', and is spaced away from the bottom of the casing to provide the water 85 of condensation receiving space or hotwell B², and is spaced away from the sides of the condenser to provide water and steam distributing channels B³ running from the ends 90 of the inlet space B' down to the hotwell B². The upper portion of the condensing core 95 100 105

proper is bifurcated to provide space for an air collecting chamber B^4 and an air cooling chamber B^5 . A baffle or partition b' forms the bottom wall of the inlet space B' and the 5 top wall of the air cooling chamber B^5 . The side walls of the latter are formed by baffles b^2 which are connected at their upper ends to the baffle b' and converge toward one another to form sloping bottom walls for 10 the chamber B^5 , and have lower vertical portions which extend downward through the upper portion of the air collecting chamber B^4 to a point above, but adjacent the lower end of that chamber, and form a 15 drainage channel for water of condensation from the air cooling chamber. A large portion of the latter is traversed by the cooling tubes b . Air passes from the bottom of the air collecting chamber B^4 into the air 20 cooling chamber B^5 through a pipe or pipes H centrally disposed between the lower portions of the partitions b^2 and shown as supported at their upper ends by arms H' soldered or otherwise connected to the pipes H 25 and to the partitions b^2 . The lower ends of the pipes H extend through the bottom wall of a trough-like member I which provides a water seal preventing the passage of vapor and air from the chamber B^4 into the cooling chamber B^5 except through the pipes H . It will be understood that the end walls of 30 the condenser casing, where those walls are not formed by the expanded and soldered together ends of the tubes b , will ordinarily be 35 formed by suitably shaped pieces of sheet metal.

A pipe I' connects the air cooling chamber B^5 at a point adjacent its upper end to a suitable exhausting means. This may be 40 a special air pump but in the arrangement illustrated the desired air exhausting effect is obtained by connecting the condenser air outlet pipe I' to the suction intake manifold of the engine. The pipe I' may well include an air valve J , i. e. a valve which 45 opens to permit the passage of air, but closes automatically to restrict the passage of steam. The vacuum or minus pressure in the cooling system is regulated by a valve 50 which opens automatically to admit atmospheric air to the system as required to prevent the vacuum or minus pressure in the system from exceeding a predetermined value. Since in the normal operation of the 55 system the pressure in the system fixes the boiling temperature in the jacket A , the admission of air may be controlled by a thermostatic valve responsive to the jacket temperature or it may be an ordinary vacuum 60 relief valve K as shown, which opens and closes as the difference between the pressure of the atmosphere and the pressure in the condenser rises above and diminishes to a predetermined value.

65 Advantageously I employ baffles b^3 at

the bottom of the condensing core to normally maintain a water seal between the lower ends of the channels B^3 and the water of condensation outlet connection D . Advantageously also I provide inclined baffles or rain plates L in the condensing core which divides the latter into sections, and each of which serves to carry water of condensation formed in the core section above it to the adjacent side channel B^3 , thereby avoiding the reduction in efficiency of the core section beneath the rain plate which would otherwise result from the films of water of condensation flowing downward from the condensing core section above the rain plate. M is a safety valve provided to limit the maximum pressure possible in the system.

In the contemplated mode of operation of the apparatus shown in Figs. 1, 2 and 3, the cooling liquid passed by the pump E into the jacket A , and not evaporated in the latter, passes with the vapor generated in the jacket through the conduit C into the inlet chamber B' of the condenser B . From the condenser inlet chamber B' , the liquid and vapor pass into the channels B^3 , the liquid passing through the channels to the hotwell B^2 , while the vapor passes from the channels into the adjacent edges of the condensing core in which substantially all of the vapor is condensed. Any air entering the condenser from the engine jacket or admitted to the condenser through the vacuum relief valve K tends to collect in the air collecting chamber B^4 , from which it is drawn into the air cooling chamber B^5 through the pipes H . The air drawn into the air cooling chamber through the pipes H is admixed with more or less vapor but this vapor is to a substantial extent eliminated by condensation in the air cooling chamber, the core tubes b of which provide, in properly designed apparatus, for an ample air cooling and vapor condensing effect. The elimination of vapor by condensation in the air cooling chamber reduces the wastage from the system to an insignificant amount, and reduces the air exhausting effect required, which may be of special importance in case a separate air exhausting pump is employed. The water of condensation forming in the air cooling chamber drains from the latter to the condenser hotwell through the channel formed between the lower portions of the baffles b^2 . The effect of the rain plates L is to reduce the amount of liquid at any one time in the intertube space of the condenser, and consequently to augment the effective condensing capacity of the latter.

With the described arrangement the coolest portion of the condensing core will normally be at the margin of the air collecting chamber B^4 so that the vapor is progressive-

ly condensed, and the air is progressively cooled as it moves through the condensing core toward the chamber B⁴. Since water of condensation formed in the air cooling chamber B⁵ escapes therefrom through a channel separate from those through which air enters the air cooling chamber, the inflowing air does not entrain and carry with it any of said water of condensation. The fact that the air passes vertically upward for an appreciable distance in traveling to the air cooling chamber B⁵ from the collecting chamber gives entrained liquid an opportunity to settle.

It will be apparent to those skilled in the art that many changes may be made in the form of the apparatus disclosed without departing from the spirit of my invention as set forth in the appended claims. Some of the modifications which may thus be made, are illustrated in Fig. 4, in which the separate air pipes H are omitted, and the channel formed by the lower portions of the partitions b², is open at its lower end to the air chamber B⁴, and this channel serves both as an uptake passage for air passing to the air cooler, and as a drain for water of condensation forming in the air channel. Fig. 4 illustrates, moreover, a different arrangement of rain plates L, each of which, in this construction, passes water of condensation from the condensing core section above it to the central air chamber B⁴. In Fig. 4, the rain plates are more numerous than in the construction shown in Figs. 1, 2 or 3, but with either form illustrated, the number of rain plates is not essential, and may be increased or decreased in number, and indeed these plates may be entirely dispensed with without affecting the general mode of operation of the apparatus. The operation of the apparatus illustrated in Fig. 4 is essentially the same as that of the apparatus illustrated in Figs. 1, 2, and 3.

Some features of the invention claimed herein may obviously be used with advantage in some cases without a corresponding use

of other novel features disclosed and those skilled in the art will understand that many changes may be made in the form of the apparatus without departing from the spirit of the invention as set forth in the appended claims.

Having now described my invention, what I claim as new and desire to secure by Letters Patent, is:

1. A condenser comprising a casing, and a condensing core and partitions therein, dividing the interior of the condenser into vertically extending water and steam distribution channels at the sides of the core, a hotwell or outlet chamber at the bottom of the condenser to which the lower ends of said channels are connected, an inlet chamber at the top of the condenser to which the upper ends of said channels open, a central air connecting chamber, and an air cooling chamber above the last mentioned chamber and communicating therewith, and means for withdrawing air from the air cooling chamber.

2. A condenser comprising a casing, and a condensing core and partitions therein, dividing the interior of the condenser into vertically extending water and steam distribution channels at the sides of the core, a hotwell or outlet chamber at the bottom of the condenser to which the lower ends of said channels are connected, an inlet chamber at the top of the condenser to which the upper ends of said channels open, a central air collecting chamber, and an air cooling chamber above the last mentioned chamber, a connection passing air from said collecting chamber to said cooling chamber, a water sealed outlet passing liquid of condensation from the cooling chamber to the hotwell, and means for withdrawing air from the air cooling chamber.

Signed at New York, in the county of New York and State of New York, this 27th day of March, A. D. 1923.

HARRY C. MALLORY.
